Primary Examiner — Martie K Holtje(74) Attorney, Agent, or Firm — Scott L. Harper; Harper Washam LLP(57) CLAIM

The ornamental design for an ornamental pack, as shown and described.

DESCRIPTION

FIG. 1 is a perspective view of an ornamental pack showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a second perspective view thereof.

The broken lines depicting stitching have been shown for the purpose of illustrating portions of the ornamental pack that form no part of the claimed design. The broken lines depicting various patches in FIG. 8 have been shown for environmental purposes only and form no part of the claimed design.
